GATE STRUCTURE

Burl W. Haskett, Huntington, Ind.

Application December 15, 1949, Serial No. 133,048

5 Claims. (Cl. 160—156)

1

This invention relates generally to an improved gate structure and has particular relation to an improved farm gate structure wherein one end of the gate is pivotally mounted to an upright support and the other end of the gate is free swinging.

One object of the invention is to provide an improved gate structure which has the singular and combined features of extreme light weight, rigidity and adjustability, simplicity of construction, a minimum of component parts and inexpensive construction.

Another object of the invention is to provide an improved farm gate structure including a telescopic tubular cross bar sag adjustor which will permit any sagging in the gate to be automatically adjusted so that the gate may be maintained in alignment.

These and other objects of the invention will be readily understood by the reference to the following description and accompanying drawings.

The improved gate of the present invention generally comprises a pair of opposing parallel horizontal standards, a pair of parallel vertical standards carrying said horizontal standards, each pair of said vertical standards comprising two opposed members formed to nest at least partially around the periphery of said horizontal standards, and clamping means connecting said vertical standards through said horizontal standards at their nesting connections, to rigidly clamp said horizontal standards between said vertical standards in all positions of lift of the gate.

In one embodiment, the invention includes a gate wherein the horizontal standard comprises tubes and in another embodiment of the invention, the vertical standards each comprise an L-shaped angle iron. In a preferred embodiment of the invention, the improved gate includes a telescoping adjustable support mounted diagonally between vertical standards. In another preferred embodiment of the invention, the improved gate includes a telescopic tubular cross-bar sag adjustor comprising an outer hollow tube provided with longitudinally and serially arranged apertures, an inner tube slidably mounted within said outer tube, an aperture engaging pawl pivotally mounted on the telescoping end of said inner tube, and a pawl engaging tongue pivotally mounted on the telescoping end of said inner tube, said apertures being longitudinally spaced to receive said pawl and tongue so that telescoping movement of the pawl into a non-apertured portion of the outer tube causes progression of the tongue into an aperture so that said tongue

2

prevents aperture locking engagement of said pawl during reverse movement into an apertured portion of said outer tube. A further embodiment of the invention generally includes this combination wherein the tongue is pivotally mounted on the pawl. A further preferred embodiment generally involves a construction wherein the tongue is spaced at a distance from the free end of the pawl substantially equal to the distance between the apertures. A further preferred embodiment generally comprises this combination wherein the telescoping tubes are each provided with an abutting spacer on their inner and outer walls respectively, the spacer on the inner tube being mounted within the telescoping portion of the tubes on the telescoping side of the outer tube spacer.

Referring to the drawings:

Fig. 1 is a front elevational view of a gate, partially broken away, embodying the present invention;

Fig. 2 is an end view of the hinged end of the gate shown in Fig. 1;

Fig. 3 is an end view of the free end of the gate shown in Fig. 1;

Fig. 4 is a cross sectional view, partially broken away, of a telescopic tubular cross bar sag adjustor embodying the present invention, showing the details of the sag adjustor shown in Fig. 1;

Fig. 5 is a view similar to Fig. 4, diagrammatically illustrating the sequence of operation, and

Fig. 6 is a view similar to Figs. 4 and 5, diagrammatically illustrating the sequence of operation.

Referring to the drawings, the improved gate generally comprises a pair of opposing parallel horizontal standards 10 carried at their hinged end by a pair of vertical standards indicated generally at 20 and carried at their free end by a pair of horizontal vertical standards indicated generally at 30 .

Additionally, the horizontal standards 10 are supported intermediate their ends by a pair of intermediate vertical standards 40 , which in the embodiment shown, are generally similar in structure to the end standards 20 and 30 . The assembled horizontal and vertical standards 10 , 20 and 30 , comprise a rectangular frame structure in which is adjustably supported a section of fencing 41 , as of galvanized interlaced wire. The fencing 41 is supported along its top and bottom edges as by adjustable lacing 42 and is adjustably mounted at its side edges to the vertical standards 20 and 30 respectively, by means of rod stretchers 43 secured to the fencing 41 and

adjustably secured, as by eyebolts 44 to the end standards 20 and 30. By virtue of this construction, the fencing may be adjusted both horizontally and vertically, by tightening or extending the lacing 42 and by tightening or extending the eyebolts 44. It will also be noted that by virtue of the present construction, the fencing 41 may be moved both horizontally and vertically between the pair of intermediate standards 40.

Each pair of standards 20, 30 and 40 comprises a pair of L-shaped angle irons 21 and 22, and a similar pair of angle irons for the intermediate standard 40.

In a preferred embodiment of the invention, the mating pairs of standards 20, 30 and 40 are die-formed as at 23, 33 to nest around the horizontal tubes 10 to maintain stability and rigidity as in all positions of lift. The clamping means connecting the pairs of vertical standards through the horizontal standards at their nesting connections comprises a rod or bolt 24 which is secured as by screw threading through aligned holes in the vertical standards and a hole in the horizontal standards. As shown, the horizontal standards 10 comprise tubes, as of tubular steel, in which event the nesting portion 23 of each standard is arcuately formed to nest around the tubing.

The hinges for the gate comprise a hanger 26 which is fastened to the hinge standards 20, as by means of a bolt and nut connection to permit vertical adjustment. The hangers 26 are adapted to pivotally carry suitable lag screws 27 adapted to be secured to a conventional gate support (not shown). The swinging end of the gate is provided with a vertically adjustable plate hasp and latch connection 38 secured to the usual fence post (not shown), as by means of a rod lock 36. In the form shown, the vertical standards extend beyond the upper limit of the top horizontal standard in order to provide a support for a barbed wire strand 11 which is secured to the end standards as by eyebolts 12 and slidably fastened to the intermediate standards, as at 13.

In a preferred form of the invention, a telescoping adjustable support designated generally at 59 is mounted diagonally between a pair of opposed vertical standards. In the preferred form shown, the telescoping adjustable support 59 is mounted diagonally between the top portion of the hinged vertical standards 20 and the bottom portion of the intermediate vertical standards 40, as by means of frame bolts 51 which provide a pivotal mounting therefor.

Referring particularly to Fig. 4, there is shown a preferred form of the telescopic tubular cross bar sag adjustor forming a part of the present invention. The adjustor comprises an outer support tube 52 and an inner support tube 53, said tubes being telescoped as shown. The outer support tube 52 is provided with longitudinally and serially arranged apertures 54 and the inner tube 53 is provided along its inner telescopic end portion 55 with an aperture engaging pawl 56 pivotally mounted, as at 57, on the inner end 55 of the inner tube 53. The aperture engaging pawl 56 is provided with an aperture engaging abutment toothed portion 58 and a sliding or plane surface 59 adapted to prevent engagement with the apertures in telescoping movement.

A pawl engaging tongue 60 is pivotally mounted on the telescoping end 55 of the inner tube 53 by means of a pivot pin 61, which in the preferred form shown, is mounted on the pawl 56. Preferably, the outer and inner telescoping tubes

52 and 53 respectively are provided with abutting spacers 65 on their inner and outer walls respectively, the spacer 65 on the inner tube being mounted within the telescoping portion of the tube on the telescoping side of the outer tube spacer 65a. For stability, an additional spacer 65b is mounted on the inner telescoping end 55 of the inner tube 53 to provide additional rigidity during the telescoping sliding operation and during the normal position of the telescoping tubes. Preferably, the spacers 65 are provided with seepage notches 66 to permit drainage of rain water. The spacer 65 is mounted in spaced relation to the spacer 65a such that the spacers will act as a limiting abutment stop means for untelescoping movement of the tubes.

Sequence of operation of telescoping adjustable support

20 As shown, in position number 1 in Fig. 5, the gate is in normal position with the spacer abutments 65 and 65a in abutting engagement and with both the pawl 56 and the disengaging tongue 60 out of engagement with the adjacent aperture 54a. In this position, the horizontal standards 10 are normally at right angles to the hanger frames or vertical standards 20, 30. As will be apparent, in the normal position the weight of the gate is carried by both the telescoping tubes 52 and 53, said tubes being in locking engagement by means of the spacers 65, 65a.

As shown, in the No. 2 position, the gate is in the first lift position. By manually lifting the gate at its free or latching end, the center or intermediate standard 40, to which the inner telescoping tube 53 is attached, causes telescoping of the said tube into the outer tube 52, thereby driving the pawl 56 and the tongue 60 past position No. 1, which is a pawl locking station and not a tube locking position, and further permitting telescoping movement into position No. 2, where the pawl 56 engages the aperture 54b by means of the pawl toothed portion 58, thereby supporting the frame of the gate in its first lift position.

45 Referring now to position No. 3, as shown, the gate may be locked in subsequent higher positions by lifting the free end of the gate until the pawl engages the desired aperture at the desired station for height.

50 It will be apparent that the gate may be lowered to normal position from any locking station by lifting the free end of the gate until the pawl 56 is past position No. 3; that is, past the last highest station, whereupon the disengaging tongue 60 drops into position No. 3, as shown, that is, into the last highest position.

55 Likewise, the gate may be lowered to any lower locking position from any locking station by lifting the free end of the gate until the tongue drops into the highest aperture (or the position No. 3 aperture), thereby lowering the gate until the tongue drops into the next lower position than that desired, and raising the gate until the pawl 65 engages the aperture at the desired height.

60 It will be apparent that the tongue may be pivotally mounted directly on the pivot rod 57 on the inner end of the inner tube and that a suitable abutment member, which may be in the form 65 of the pivot mounting 61, may be provided as engaging means for the tongue so that the tongue may move the pawl out of the aperture engaging position upon movement of the tongue caused by sliding engagement with an aperture.

70 75 While the invention has been disclosed and de-

scribed in its preferred embodiment, it will be understood that various modifications may be made therein by those skilled in the art, and it is intended that all such variations as come within the spirit and scope of the appended claims shall be thereby covered.

I claim:

1. A gate comprising a frame including at least two spaced vertical members, a first of said vertical members being provided with means for holding it in a vertical position, a telescoping sag adjustor extending diagonally from said first vertical member to the other unsecured vertical member, said sag adjustor comprising a tubular outlet member provided with longitudinally and serially spaced apertures, an inner assembly including a cylindrical member having one end telescoping within said tubular member, and a pawl pivotally mounted in extension of the telescoping end of said inner cylindrical member, a tongue pivotally mounted on said assembly, said tongue being so positioned and of such length that in one position it covers the pawl, whereby on movement of said inner assembly in one direction, said tongue engages one of said apertures to position itself over the pawl to prevent the pawl from engaging the apertures, and on movement of the inner assembly in the other direction, the tongue engages one of said apertures to pivotally reverse its position and thereby permit said pawl to engage a desired aperture, the movement of said telescoping sag adjustor members being effected by vertical movement of the end of the gate frame adjacent the unsecured vertical member.

2. The combination as set forth in claim 1 wherein said pawl includes an aperture engaging tooth and a plane portion and said pivoted tongue is mounted on the plane portion of the pawl.

3. The combination set forth in claim 1 wherein said pawl includes an aperture engaging tooth and a plane portion and said pivoted tongue is mounted on said pawl, said tongue being spaced at least a distance from the free end of the pawl substantially equal to the distance between the apertures.

4. The combination set forth in claim 1 wherein the inner and outer telescoping members are each provided with an abutting spacer on their outer and inner walls, the spacer on the inner wall so being mounted on the telescoping portion of the members on the telescoping side of the outer member spacer.

5. A parallelogram type gate comprising a pair of opposing parallel horizontal standards, a pair of parallel vertical standards carrying said horizontal standards, each pair of said vertical standards comprising two members formed to nest at least partially around the periphery of said horizontal standards, clamping means connecting said vertical standards through said horizontal standards at their nesting connection, to rigidly clamp said horizontal standards between said vertical standards in all positions of lift of the gate, a first of said vertical standards being provided with means for holding it in a vertical position, a telescoping sag adjustor extending diagonally from said first vertical standard to the other unsecured vertical standard, said sag adjustor comprising a tubular outer member provided with longitudinally and serially spaced apertures, an inner assembly including a cylindrical member having one end telescoping within said tubular member, and a pawl pivotally mounted in extension of the telescoping end of said inner cylindrical member, a tongue pivotally mounted on said assembly, said tongue being so positioned and of such length that in one position it covers the pawl, whereby on movement of said inner assembly in one direction, said tongue engages one of said apertures to position itself over the pawl to prevent the pawl from engaging the apertures, and on movement of the inner assembly in the other direction, the tongue engages one of said apertures to pivotally reverse its position and thereby permit said pawl to engage a desired aperture, the movement of said telescoping sag adjustor members being effected by vertical movement of the end of the gate frame adjacent the unsecured vertical standard.
